PAINT CAN ATTACHMENT

Eugene C. Day, San Mateo, Calif.

Application April 16, 1947, Serial No. 741,893

3 Claims. (Cl. 220—90)

1

The present invention relates to paint can attachments and particularly to that type of attachment providing a brush wiping strip or element.

It is an object of the present invention to provide a paint can attachment which may be easily attached to or removed from a conventional paint can to provide a wiping element upon which the paint brush may be wiped.

It is a further object of the present invention to provide such a device which is adapted for temporary attachment to the can and which may be removed therefrom and used upon other cans.

Other objects and advantages of the present invention will be apparent from the following description taken in conjunction with the accompanying drawings in which:

Figure 1 is a top plan view of a paint can showing my attachment.

Figure 2 is a cross sectional detail taken along the line 2—2 of Figure 1.

Figure 2 is a cross-sectional detail taken along the line 3—3 of Figure 1, and

Figure 4 is a side elevational view taken along the line 4—4 of Figure 1.

I have shown my paint can attachment in conjunction with a conventional paint can 10 which, as is well known, is provided with an inwardly extending lip 11 and an opening or mouth 12.

Generally when one is painting, the brush is inserted into the can through the opening 12, dipped into the paint, and then wiped against the lip 11. All who have painted appreciate the resulting difficulties.

My paint can attachment consists generally of a piece of heavy spring wire which is formed to provide a wiper strip 15, of suitable predetermined length. At each end of wiper strip 15 the wire is helically wound as shown to provide a pair of spring portions 16 and 17 which extend generally at right angles to the longitudinal axis of the wiper strip 15. While the number of coils in helical spring portions 16 and 17 may vary, I prefer that there be at least four or five such coils. Helical spring portion 16 terminates in a handle portion 18 and helical spring portion 17 terminates in a hook 19.

Handle 18 is adapted to extend radially of the can where it may be readily grasped and where it will be free from any contact with the can, the paint, or the brush. Hook 19 on the other hand is adapted to overlie the lip portion 11 and engage can 10 generally as shown in Figure 2.

2

The method of attaching a device to the can may briefly be described as follows: Hook 19 is placed over the lip 11 so that its outer end engages the sides of the can 10 generally as shown in Figure 2. Helical spring portion 17 is urged into position against the lip 11 in such a manner that lip 11 engages one of the grooves 17a presented by the outer portion of the helical spring portion 17. Handle 18 is then urged generally in the direction shown by the arrow in Figure 1 whereby handle 18, spring portion 16 and wiper 15 pivot generally about helical spring portion 17 generally to the dotted line position shown in Figure 1. When the wiper strip 15 and helical spring portion 16 are within the opening 12 of can 10 handle 18 is released whereupon helical spring 16 engages the lip 11 in substantially the same manner as helical spring 17 has previously engaged lip 11 and the device is held in the full-line position shown in Figure 1 by the spring effect of hook 19 engaging the outer edge of can 10 and helical spring portion 16 engaging the lip 11.

When the device is so placed in the can, one may insert the brush through the opening 12 into the paint within the can 10 and then wipe the surplus paint from the brush upon the wiper strip 15.

The entire device may be removed from the can by merely urging the handle 18 in the direction shown by the arrow until helical spring portion 16 is disengaged from lip portion 11 whereupon wiper strip portion 15, spring portion 16 and handle 18 can be raised upwardly clear of the can and hook 19 disengaged therefrom.

The helical spring portions 16 and 17 present a plurality of grooves 16a and 17a which are adapted to engage lip 11. By selecting the groove 16a or 17a which one places in engagement with the lip 11 one can predetermine or gauge the depth of the wiper strip 15 within the can opening 12.

I claim:

1. In a device adapted to be inserted in the mouth of a paint can having an inwardly extending lip, a wiper strip, means for attaching said wiper strip to said can including a pair of helical springs formed integrally with said wiper strip and adjacent the ends thereof and extending at right angles to the longitudinal axis of said wiper strip, one of said spring portions terminating in a handle adapted to extend outwardly of said can when said device is inserted in the mouth of said can, the other of said spring portions terminating in a hook adapted to extend

over said lip and engage the outer surface of said can when said device is positioned in said can with its adjacent spring portion engaging the lip of said can, said second spring serving to urge said first spring and said handle into engagement with the lip of said can and to retain the same in that position, said spring portions also presenting a plurality of grooves adapted to engage said lip whereby the depth of said wiper strip within said can opening may be predetermined.

2. In a device adapted to be inserted in the mouth of a paint can provided with an inwardly extending lip, a wiper strip, a pair of helical springs formed at the ends of said wiper strip 15 and at right angles to its longitudinal axis, one of said spring portions terminating in a hook adapted to extend over said lip and position said device by engaging the outer surface of the can, said spring portion urging said second spring into 20

engagement with the lip of said can to retain the device in position.

3. A device as described in claim 2, said helical springs providing a plurality of grooves adapted to engage said lip whereby the depth of said wiper strip within said can opening may be predetermined.

EUGENE C. DAY.
